FRANCIS A. MAHAN AND CHARLES H. McCARTHY, OF WATERBURY, CONNECTICUT.

AUTOMOBILE HOOD COVER.

Application filed January 17, 1925. Serial No. 3,194.

To all whom it may concern:

Be it known that we, FRANCIS A. MAHAN and CHARLES H. McCARTHY, citizens of the United States, and residents of Waterbury, county of New Haven, and State of Connecticut, have invented certain new and useful Improvements in Automobile Hood Covers, of which the following is a specification.

10 This invention relates to automobile hood covers, and more particularly to a device for use in winter to prevent freezing of the water in the cooling system of the engine.

One object of this invention is to provide 15 a hood cover made from a single piece of sheet material and adapted to be folded into position over the hood and secured thereto whenever desired.

A further object is to provide a hood cover 20 of the above nature which will be simple in construction, inexpensive to manufacture, easy to install, compact in size, ornamental in appearance, and very efficient and durable in use.

25 With these and other objects in view, there have been illustrated on the accompanying drawings, two forms in which the invention may be conveniently embodied in practice.

Fig. 1 represents a perspective view of 30 the preferred form of hood cover as it appears while in flat condition before being folded and placed in position over the hood.

Fig. 2 is a similar perspective view of a 35 modified form of hood cover also embodying the invention.

Fig. 3 is a sectional view, partly broken away, of the hood cover shown in Fig. 1, as it appears when in position on the hood of an automobile.

40 Fig. 4 is a perspective view, with parts broken away, of the preferred form of hood cover, as it appears when assembled in position on the hood of an automobile.

Referring now to the drawings in which 45 like reference numerals denote corresponding parts throughout the several views, the preferred form of hood cover, which is illustrated in Figs. 1, 3, and 4, comprises a hood section 10, originally flat and rectangular in shape and having its side ends 11 and 12 bent inwardly upon themselves at 13 and 14 for reinforcement. The forward edge of the hood section 10 is provided with a plurality of slits 15 forming tabs 16, which 55 are adapted to be bent laterally in front of

the radiator into overlapping engagement with each other, so as to prevent possibility of the tearing or buckling of said hood cover when it is folded into operating position.

The hood section 10 has a circular aperture 17 at its forward central portion adapted to fit over the radiator filling inlet 18, as clearly shown in Figs. 3 and 4.

The reinforced side ends 11 and 12 of the hood section 10 are adapted, when the hood cover is folded into position, to lie flat 60 against the doors of the hood, and to be secured to said doors by detachable clips 19, said clips preferably being substantially U-shaped, and formed from resilient sheet 65 metal.

Connected to the central part of the front of the hood section 10 is a relatively narrow neck member 20, said neck member being 70 in turn connected to a radiator section 21 adapted to lie vertically in front of the radiator of the automobile. The neck member 20 is provided with a pair of central apertures 22 and 23, having the same diameter 75 as the aperture 17, and adapted to align therewith, when the member 20 is folded along the dotted lines 23^a, 23^b, and 23^c. It will be understood that when the neck member 20 is thus folded, the connection between the hood section 10 and the radiator 80 section 21 will be strongly reinforced. By means of this construction, there will be no danger of tearing at the neck which is the point where the greatest strain is likely to 85 occur in practice.

The radiator section 21 is generally 90 rectangular in shape, and as herein illustrated, has straight side and bottom edges, and curved upper corners 24, which may be made to correspond with the shape of the radiator. 95 The side edges of the radiator section 21 are adapted to be secured to the tabs 16 of the hood section in any suitable manner, as by rivets, snap fasteners, cement, etc.

In order to permit the passage of a small 100 amount of air through the radiator when the car is running and thereby to prevent overheating of the engine, the radiator section 21 is provided with a central flap 25 cut out from the material of said section, said flap 105 having a pair of snap fasteners 26 and 27 at its bottom edge adapted to engage a pair of studs 28 located on the radiator section above said flap 25.

In order to reinforce the sides of the rec- 110

tangular opening surrounding the flap 25, a rectangular ring 29 of stiff paper or other suitable material may be employed.

In the modified form of the invention shown in Fig. 2, the construction of hood cover is identical with that of the cover illustrated in Figs. 1, 3, and 4, except that the hood section 10 is directly connected with the radiator section 21 without the use of any intermediate neck member, and the side edges 30 and 31 of the hood section are not reinforced.

It will be understood that either form of hood cover herein disclosed may be constructed from any suitable waterproof, heat-insulating, material, but stiff paper is deemed to be preferable.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an automobile hood cover, a hood section adapted to lie against the outer surface of an engine hood, a radiator section adapted to lie in front of the radiator, a fold-

able neck member for joining said hood section to said radiator section, said cover being formed of a single piece of flat sheet material and bent into contact with the outer surfaces of said hood and radiator. 40

2. In an automobile hood cover, a hood section adapted to lie against the outer surface of an engine hood, a radiator section adapted to lie in front of the radiator, a foldable neck member for joining said hood section to said radiator section, said hood section having a central aperture in its front portion to fit over the radiator filling inlet, said cover being formed of a single piece of flat sheet material and bent into contact with the outer surfaces of said hood and radiator. 45

3. In an automobile hood cover, a hood section adapted to lie against the outer surface of an engine hood, a radiator section adapted to lie in front of the radiator, a foldable neck member for joining said hood section to said radiator section, said hood section having a central aperture in its front portion to fit over the radiator filling inlet, said neck member having a pair of apertures 55 adapted to fit about said radiator inlet, and adapted when said neck is folded to align with the aperture in said hood portion, said cover being formed of a single piece of flat sheet material and bent into contact with 60 the outer surfaces of said hood and radiator. 65

In testimony whereof, we have affixed our signatures to this specification.

FRANCIS A. MAHAN.
CHARLES H. McCARTHY.
